PEA SHELTER

Anthony Flanagan, Ardmore, Pa.

Application October 4, 1939, Serial No. 297,796

4 Claims. (Cl. 130—30)

This invention relates to an improved type of pea sheller.

It is an object of this invention to provide a durable and inexpensive device, adapted for household use, which will facilitate and expedite the task of shelling peas, as the common green pea.

The manner in which this and further objects are accomplished will appear from the following description of a preferred embodiment of my invention, read in connection with the accompanying drawing, in which:

Figure 1 is a perspective view of a preferred embodiment of my invention, showing the manner in which it is used;

Figure 2 is a fragmentary side elevation, partly in section, of the device shown in Fig. 1; and

Figure 3 is a detail, plan view of a portion of the device.

The pea sheller is in accordance with my invention, as shown in the drawing, is provided with a base plate 1, curved in cross-section throughout the greater part of its length, but flared outwardly and downwardly at its forward end 3 to form an approach and guide for the pea-pod to be shelled. Secured to the upper (when the device is in its normal position for use) surface of the plate 1 is a relatively thin knife member 5 positioned with its cutting edge 7, which extends at right angles to the plane of the plate 1, about in line with the point at which the flared portion 3 begins.

A guide and spreader 9, which in the construction shown in the drawing is formed from a tubular member, is secured to the plate 1, but is spaced therefrom at its forward end by the knife 5 to which it is also secured. The forward end of the member 9 is cut away at an acute angle, on the order of 30°, to the axis of the tube, to form an opening 11 bounded by side walls 13 which converge downwardly and forwardly to a point 15. The edges of these walls as well as the point 15 are rounded and blunt.

The spreader 9 is secured in position with the opening 11 directly above the knife 5 and the point 15 axially in line with and slightly forward of the knife edge 7. There is thus formed a channel 17, between the walls 2 of plate 1 and the walls 13 of member 9, roughly semi-annular in form but broadening at its forward end, and interrupted at its lowest point by the knife 5.

For convenience in use the device may be mounted on a tripod formed by a rear leg 19 secured to base plate 1 and a pair of front legs 21 pivotally secured to the base 1 so that they

may be folded back when the device is not in use. A stop may be provided to prevent movement of the legs 21 beyond proper open position. In the drawing the portion 3 of the plate 1 cooperates with a right angle bend in the legs 21 to form a stop. The leg 19 is shorter than the legs 21 so that the sheller is positioned for use at an angle of about 45° to the horizontal.

The legs 21 are connected by a brace 23, which conveniently may be provided with a notch 25 and removable cutting blade 27 angularly disposed within the notch, for severing the ends from pea-pods prior to the shelling operation.

In using the device, the operator takes a pea-pod and first severs one end therefrom, either by use of the blade 27 or otherwise, so as to form a small opening into the interior of the pod. The pod is then guided along the portion 3 of plate 1 so that point 15 is inserted in the opening just formed in the end of the pod, as shown by the dotted lines in Fig. 1. The operator then moves the pod rearwardly along the member 9, maintaining a gentle downward pressure, and as the pod moves rearwardly the knife 5 splits the pod, which passes within the channel 17, while the peas are freed from the pod by either the point 15 or the walls 13 (at 14) and drop through the opening 11 into the interior of member 9 whence they are discharged through the open lower end 10 into a vessel that may be placed there to receive them.

What I claim and desire to protect by Letters Patent is:

1. In a pea sheller, a base plate, a cutting blade secured to the upper face of said base plate with its cutting edge extending substantially at right angles thereto, a tubular member having an opening at one end thereof on a plane lying at an acute angle to its axis, whereby the walls of the opening converge to a point, said tubular member being positioned upon said cutting blade and parallel thereto, with the said point spaced from said base plate only by the length of said cutting edge and positioned in line with and slightly forward of said cutting edge.

2. In a pea sheller, a base plate, a cutting blade secured to the upper face of said base plate with its cutting edge extending substantially at right angles thereto, a tubular member having an opening at one end thereof on a plane lying at an angle of about 30° to its axis, whereby the walls of the opening converge to a point, said tubular member being positioned upon said cutting blade and parallel thereto, with the said point spaced from said base plate only by the

length of said cutting edge and positioned in line with and slightly forward of said cutting edge.

3. In a pea sheller, a base plate, a guide member having a base and a pair of diverging guide vanes extending upwardly therefrom, said guide member being positioned with its base in spaced relation to said base plate, a cutting member positioned between said guide member and said base plate with its cutting edge bridging the space between the base of the guide member and the

base plate, and a supporting leg assembly for said base adapted to support it with a rearward slope of about 45° to the horizontal.

4. In a pea sheller, a base plate, a cutting blade secured to the upper face of said base plate with its cutting edge extending substantially at right angles thereto, and a tubular guide member positioned upon said cutting blade and parallel thereto, said member extending slightly forwardly of the cutting edge of said blade. 10

ANTHONY FLANAGAN.
